RUBBER HEEL

Rocco Conticchio, Mount Vernon, N. Y., assignor
of one-half to John W. Guzzetta, Mount Ver-
non, N. Y.

Application April 20, 1937, Serial No. 137,973

2 Claims. (Cl. 36—35)

My present invention relates to rubber heels, and more particularly to such devices as are adapted for use in connection with men's, women's or children's shoes. It is the main object 5 of the present invention to provide a rubber heel which is simple in construction, easy and economical to fabricate and assemble and admirably adapted to perform the functions intended as hereinafter more specifically set forth.

10 In the accompanying specification, I shall describe and in the annexed drawing show an illustrative embodiment of the rubber heels of the present invention. It is, however, to be clearly understood that changes in the details of construction therein may be made without the use of the inventive faculties and within the scope of the claims hereto appended.

15 In the accompanying drawing, Fig. 1 is a partial longitudinal sectional, partial side elevational view of a rubber heel made in accordance with the principles of the present invention attached to a shoe.

Fig. 2 is a bottom plan view, and

Fig. 3 is a transverse sectional view taken along 25 line 3—3 of Fig. 2.

Referring now more in detail to the aforesaid illustrative embodiment of the rubber heels of the present invention, and with particular reference to the drawing illustrating the same, numeral 10 generally designates the rear portion of a shoe, particularly shown here as a man's shoe, but which, it is to be understood, may be a woman's or child's shoe. Such shoe is provided with a leather or wooden heel 11 which may be built up 30 of layers, as specifically shown here, or may be solid.

The heel 11 is provided with a centrally located depression 12, the shape of which conforms with the shape of the heel and the depth of which 40 should be less than the raised portion of the rubber heel which will hereinafter be referred to.

A rubber heel 13 adapted to be secured to the shoe 10 is conventional in shape but has on its inner surface the marginal cupped portion 14, 45 from the inner limits of which rises a raised portion or platform 15. The upper surface of the platform 15 is slightly below the rim 16 of the marginal cupped portion 14. On the outer surface 17 of the heel, I provide the anti-skid 50 raised portions 18 and it is to be noted that the side walls 19 of the heel are disposed at an angle other than a right angle to the bottom surface 17, converging toward the platform 15.

The heel 13 is fixed to the shoe 10 by locating 55 the platform 15 within the depression 12 of the

leather heel 11 after which the rubber heel is flexed by exerting pressure adjacent the center of the under surface 17 and the heel is held in this position by driving a nail 20 therethrough to anchor in the leather portion 11. 5

The under or wearing surface of the heel is, therefore, concave as best seen in Fig. 1 of the drawing, and intermediate the marginal portions 15 and the leather heel 11 and the top surface of the platform 15 and the heel 11, there is provided air pockets 21 and 22.

It will thus be seen that in view of the flexed position in which the heel is held by the nail 20, resilience is added thereto thus lessening the shock to the wearer caused by the pounding of 15 the heel upon a hard surface. This shock is further reduced by the provision of the air pockets 21 and 22 which act as cushions to absorb the shock given the outer surface of the heel.

This completes the description of the aforesaid 20 illustrative embodiment of the rubber heels of the present invention. It will be noted from such description that the rubber heels of the present invention are simple in construction, easy and economical to fabricate and assemble, and 25 admirably adapted to perform the intended functions. Other objects and advantages of the devices of the present invention will readily occur to those skilled in the art to which the present invention relates. 30

What I claim as my invention is:

1. In combination with a conventional heel provided with a depression in its outer surface, a rubber heel including a main body portion, cupped marginal portions formed with said main 35 body portions, a locating platform rising from the inner surface of said main body portion and extending into the depression in the conventional heel, and means to affix said main body portion to the conventional heel and hold the same in 40 a flexed position.

2. In combination with a conventional heel provided with a depression in its outer surface, a rubber heel including a main body portion, cupped marginal portions formed with said main 45 body portions, a locating platform rising from the inner surface of said main body portion and extending into the depression in the conventional heel, and means to affix said main body portion to the conventional heel and hold the same in 50 a flexed position, said cupped marginal portions and said locating platform cooperating with the adjacent surfaces of the conventional heel to form shock absorbing cushions.

ROCCO CONTICCHIO. 55
